Geo. B. Maring Stamford Connecticut

Letters Patent No. 217 dated April 10th 1851

The schedule referred to in these letters patent and matter
parts of the same

To all whom it may concern: Be it known that Geo B
Maring of Stamford, Fairfield County & State of Con-
necticut have invented a new and useful design on
the patterns and ornaments of stoves, and I hereby de-
clare that the following is a full and correct description

The name by which I designate it is "The Republic"

To enable others to make and use my invention I proceed
to describe it by reference to the four sheets of drawings
hereunto annexed and making part of this specification

Fig. 1 Perspective view of the stove - drawn half the size
of the other figures.

2 The form of the large oven doors of which the border is
the same as shown in fig. 11.

" 3 " " " small oven doors.

" 4 The top piece or cover of the portable furnace or sum-
mer piece.

" 5 Bottom piece of the stove.

" 6 Elevation of the front with the summer piece
placed on the hearth

" 7 Ornament full size placed over the large oven
doors, on the side pieces

" 8 Ornament full size, on the large doors at the
sides of the stove - see fig. 2.

" 9 Ornament in the upper corners of the large oven doors

" 10 Ornament in the lower corners of the large doors.

" 11 One of the small oven door's full size, with the
Phoenix ornament.

2

Res. 217

" 12. The lower small doors with the back door arrangement,
the border being the same as that of the small doors fig. 11.—
That I claim as my invention and desire to secure by
this patent is the new and useful design for bookends
of which I call "the Republic", as appears from the
foregoing specification and the drawing attached thereto.—

Witness,

Everett H. Hansen
R. C. Hanson Jr.
